UNITED STATES PATENT OFFICE.

ULYSSES G. MCQUEEN, OF NEW YORK, N. Y., ASSIGNOR TO GRANT PULLEY & HARDWARE CO., OF NEW YORK, N. Y., A CORPORATION OF NEW YORK.

SASH-PULLEY.

1,129,998.

Specification of Letters Patent.

Patented Mar. 2, 1915.

Application filed December 12, 1912, Serial No. 736,276. Renewed January 21, 1915. Serial No. 3,633.

To all whom it may concern:

Be it known that I, ULYSSES G. MCQUEEN, a citizen of the United States, and a resident of the city, county, and State of New York, have invented a new and useful Improvement in Sash-Pulleys, of which the following is a specification.

Heretofore when three sashes have been hung side by side so as to form a triple window, and the weights have been suspended in wells at each side of the windows but not between any two of them, it has been necessary to fix some of these pulleys in the window frame before the same is inserted in a building, with the result that when a pulley became broken or otherwise injured so as to be unfit for use, it has been impossible to repair or renew the pulley without mutilating the frame or the building.

The object of my invention is to provide a pulley which can be either inserted or removed after the frame is in place, and after the building is otherwise complete, so as to 25 in no way interfere with the frame or other parts of the building when the pulleys and sashes are inserted. This object is accomplished by my invention, one embodiment of which is hereinafter set forth.

For a more particular description of my invention, reference is to be had to the accompanying drawings, forming a part hereof, in which—

Figure 1 is a sectional view of a frame provided with my improved pulley; Fig. 2 is a plan view of the structure shown in Fig. 1; Fig. 3 is a side elevation of my improved pulley in its detached condition; and Fig. 4 is a plan view of the structure 40 shown in Fig. 3.

Throughout the various views of the drawings, similar reference characters designate similar parts.

In Fig. 1 is shown the left-hand side of 45 the upper portion of a frame, in section, of a triple window, the other corner being symmetrical therewith, so that a description of one will answer for both. The frame 1 is placed below a lintel (not shown) and is provided with four wells, 2, 3, 4 and 5, in which suitable sash weights 6 are hung by chains 7 and 8, or other suitable means. These chains 7 and 8 pass over suitable pulleys 9 and 10, both of which are mounted in 55 the top of the frame 1, the pulley 10 being

a double pulley, that is, a pulley with two sheaves mounted on a single spindle, so that one end of the chain 8 can go over one sheave and the other end over the other, with the result that one weight can balance 60 a sash. The chain 7 balances only half a sash, and so runs over a single sheave 11 mounted on a spindle 12 in the casting or hood 13 of the pulley 9. The casting 13 is provided with a suitable base 14 with an interior slot 15, into which extend suitable guiding lugs 16 between which is formed a suitable groove that receives a flange 17 at the lower edge of the casting 13. This casting 13 is preferably made in the shape of a 70 hood so as to cover the sheave and protect the rear face of the same. The front and lower faces are open so as to allow for the insertion or removal of the chain 7. A portion of the casting 13 is cut away at 18 to 75 form a recess which will enable this hood or casting to get close to the pulley 10 without interfering with the same.

From the foregoing the use and operation of my improved pulley will be readily understood. When the sash frame is built, suitable mortises are made for the pulleys 9 and 10 and the other pulleys (not shown), and suitable openings are made for the chains. The base 14 for each pulley 9 80 is also inserted in place and secured by suitable screws 19 passing through perforations made for the purpose. When the sash frame is in the building and ready for use, a casting or hood 13 for each base 14 with 85 its sheave 11 mounted on a spindle 12 is passed through the opening left for the pulley 10 and shifted until the flange 17 engages the lugs 16 and is shoved home so that the base 14 securely holds this casting 90 or hood 13. The chain 7 and the parts connected therewith are then put in position, the chain passing around the sheave 11 and then the pulley 10 is put in place after 95 which the chain 8 and the parts connected therewith are suitably mounted. The placing of the pulley 10 secures the casting 13 so that the same cannot be moved enough 100 so as to interfere in any way with the operation of the pulley 9.

While I have shown and described one embodiment of my invention, it is obvious that it is not restricted thereto, but is broad enough to cover all structures that come 110 within the scope of the annexed claims.

What I claim is:

1. In a device of the class described, a slotted base with a slot extending to its outer edge, a series of inwardly projecting 5 lugs and a hood with a flange adapted to pass into said slot and between said lugs and to be held between the same whereby the hood may be inserted or removed through the end of the base.
- 10 2. In a device of the class described, a slotted base with means therein for receiving a portion of a removable hood, a re-

movable hood with a portion extending into said base, said hood and base being so connected that the hood may be slid in or out of the base from one end of the base.

In testimony whereof I have signed my name to this application in the presence of two subscribing witnesses this 3rd day of December, 1912.

ULYSSES G. McQUEEN.
